Des. 187,800
Patented May 3, 1960

187,800

TOY DOLL OR SIMILAR ARTICLE

Warren A. Bellstrom, La Grange Park, Ill.

Application August 25, 1958, Serial No. 52,360

Term of patent 14 years

(Cl. D34—4)

Fig. 2

I claim:

The ornamental design for a toy doll or similar article, substantially as shown.
